CLAIM

I claim the ornamental design for a lighting device, as shown and described.

DESCRIPTION

FIG. 1 is a perspective view of a lighting device showing my new design, in a compact configuration, and as viewed from the top and one side.

FIG. 2 is a front elevation view of the lighting device of FIG. 1 in the compact configuration.

FIG. 3 is a top plan view of the lighting device of FIG. 1 in the compact configuration.

FIG. 4 is a first side elevation view of the lighting device of FIG. 1 in the compact configuration.

FIG. 5 is a back elevation view of the lighting device of FIG. 1 in the compact configuration.

FIG. 6 is a second side elevation view of the lighting device of FIG. 1 in the compact configuration.

FIG. 7 is a bottom plan view of the lighting device of FIG. 1, in the compact configuration; and,

FIG. 8 is a perspective view of the lighting device of FIG. 1 in a partially expanded configuration, as viewed from the top and one side thereof.

The details shown in broken lines are for illustrative purposes only and form no part of the claimed design.
